MASTER CONTROL UNIT FOR A CENTRALIZED OIL LUBRICATING SYSTEM

Robert M. Wolaver, South Euclid, Ohio, assignor to Eaton
Yale & Towne Inc., Cleveland, Ohio, a corporation of
Ohio

Original design application Apr. 3, 1967, Ser. No. 6,497.
Divided and this application Jan. 22, 1968, Ser. No.
10,594

Term of patent 14 years

U.S. Cl. D52—2
Int. Cl. D23—01; D31

FIG. 7

FIG. 8

FIG. 9

FIG. 10

FIG. 11

FIG. 12

FIG. 1 is a perspective view of a master control unit for a centralized oil lubricating system and showing the front and one side thereof;

FIG. 2 is a right side elevational view thereof;

FIG. 3 is a front elevational view thereof;

FIG. 4 is a top plan view thereof;

FIG. 5 is a rear elevational view thereof;

FIG. 6 is a bottom plan view thereof;

FIG. 7 is a perspective view of a second embodiment of a master control unit for a centralized oil lubricating system and showing the front and one side thereof;

FIG. 8 is a right side elevational view thereof;

FIG. 9 is a front elevational view thereof;

FIG. 10 is a top plan view thereof;

FIG. 11 is a rear elevational view thereof;

FIG. 12 is a bottom plan view thereof;

FIG. 13 is a perspective view of a third embodiment of a master control unit for a centralized oil lubricating system showing the front and one side thereof;

FIG. 14 is a right side elevational view thereof;

FIG. 15 is a front elevational view thereof;

FIG. 16 is a top plan view thereof;

FIG. 17 is a rear elevational view thereof; and

FIG. 18 is a bottom plan view thereof.

This application is a divisional application of my co-pending application Ser. No. D. 6,497, filed Apr. 3, 1967. I claim:

The ornamental design for a master control unit for a centralized oil lubricating system, as shown and described.
